UNITED STATES PATENT OFFICE.

ELMER SAS, OF NEW YORK, N. Y.

DRINK MIXER.

Application filed July 8, 1922. Serial No. 573,565.

To all whom it may concern:

Be it known that I, ELMER SAS, a citizen of Hungary, and resident of the city of New York, in the county of Bronx and State 5 of New York, have invented certain new and useful Improvements in Drink-Mixers, of which the following is a specification.

The present invention relates to improvements in agitating devices of the type generally used for mixing beverages at soda 10 water fountains.

The main object of the invention is to provide a device of the type mentioned, whereby a plurality of drinks may be 15 separately mixed at a time, the agitators being adapted to be operated successively, selectively or simultaneously.

Another object of the invention is to produce a drink mixer of the character mentioned, which is simple in construction, efficient in operation, and the electric driving mechanism of which is automatically set in motion when any one of its agitating elements is brought into operative position.

25 A further object of the invention is to provide an agitating element which thoroughly mixes the liquid and at the same time aerates the drink.

With these and other objects in view, 30 which will more fully appear as the nature of the invention is better understood, the same consists in the combination, arrangement and construction of parts hereinafter described, pointed out in the appended 35 claims and illustrated in the accompanying drawings, it being understood that many changes may be made in the size and proportion of the several parts and details of construction within the scope of the appended 40 claims, without departing from the spirit or sacrificing any of the advantages of the invention.

One of the many possible embodiments 45 of the invention is illustrated in the accompanying drawings, in which:

Figure 1 is a top plan view of a drink-mixer constructed in accordance with the present invention; Fig. 2 is a section taken on line 2—2 of Fig. 1; Fig. 3 is a section taken on line 3—3 of Fig. 2; Fig. 4 is a section taken on line 4—4 of Fig. 1, on a larger scale; Fig. 5 is a section taken on line 5—5 of Fig. 4; Fig. 6 is a central vertical section, on a larger scale, taken 55 through the mechanism carrying one of the agitating elements; Fig. 7 is a perspective

view of the circuit closing element of the device; Fig. 8 is an elevation, on a larger scale, of one of the agitating elements; and Fig. 9 is a section taken on line 9—9 60 of Fig. 8.

In the drawings, the numeral 10 indicates a base plate, from which rises centrally a hollow frame member 11, carrying at its upper end a horizontally extending substantially dome-shaped frame member 12, that is also secured to a plurality of pairs of vertically extending tubular posts 13. These posts are fixed in any suitable manner to the base plate 10 and surround the frame 65 member 11. The frame member 11 is substantially funnel-shaped at its upper end, as shown at 14, the said funnel-shaped end, together with the dome-shaped member 12, forming a housing, in which the driving 70 elements of the mixer are located.

Within the frame member 11 is disposed an electric motor 15, having a vertically extending driving shaft 16. To this shaft is fixedly secured in any suitable manner a 80 friction disk 17, which is disposed within the housing above referred to. With this friction disk are adapted to be brought into engagement, in a manner hereinafter to be described, a plurality of driven disks 18. Each 85 of these disks is carried by an agitator shaft 19, which is suitably mounted in bearings on a head 20. Each of these heads is carried by a pair of tubes 21, adapted to telescope into a pair of posts 13 above referred to. Within each tube 21 is disposed a longitudinally extending U-shaped wire piece 22, the ends of the wire piece being securely fastened to a plug 23 at the upper end 90 of the tube. With this wire piece cooperates 95 a U-shaped wire piece 24, the ends of which are fastened to the respective post 13 adjacent its lower end. The two wire pieces are disposed in planes at right angles to one another and cross each other, so that 100 their bights will be brought into engagement when the respective tube 21 is drawn out of the post 13, thereby preventing a disengagement of the elements mentioned.

A helical spring 25 is located in each tube 105 21, the upper end of said spring being attached to the respective plug 23 and the lower end thereof to the respective standard 13. The tendency of this spring is to cause the respective head 20 to move upwards into 110 the position shown in dotted lines in Fig. 2 of the drawings.

To each shaft 19 is detachably fastened an agitating element 26, extending vertically downwards and including an upper cylindrical portion 27, that is secured to the shaft 19, the remainder of the agitating element being substantially elliptical in transverse cross-section and provided with a longitudinal groove 28 in each of the opposite faces thereof. The lower end of the agitating element is split, as shown at 29, the two split portions being bent outwards in opposite directions. The purpose of this arrangement will appear hereinafter.

In each head 20 is oscillatably mounted a vertical spindle 31, preferably in alignment with the respective driven shaft 19. To the upper end of the spindle is attached a knob 32 and to the lower end thereof a bell 33, that covers the respective driven disk 18. Each bell carries a shoulder 34, co-acting with a stop 35 on the respective head 20, to limit the oscillating movement of the spindle. Each bell is furthermore provided with an outwardly projecting horizontal lug 36, which is adapted to pass through a notch 37 in the frame member 12 and to co-operate with a downwardly extending nose 38 on a star wheel 39. This star wheel is oscillatably mounted on a pin 40 on the frame member 12 and carries a roller 41. The roller is mounted in operative relation to an electric switch 42, that includes a spring contact 43. This spring contact is fixed by a terminal screw 44 to an insulating plate 45, the latter being attached in any suitable manner to the frame portion 12. The free end of the spring is adapted to contact with a terminal screw 46 on the insulating plate. A wire 47, leading to the motor 15, is clamped to the spring 43 by the aid of the terminal screw 44, while another wire, denoted by the numeral 48, leads to one of the terminals of the source of electric energy. The other terminal of said source is connected by a wire 49 with the terminal screw 46. A spring 50, secured to the star wheel 39 and the frame member 12, has a tendency to shift the star wheel 39 into the position shown in dotted lines in Fig. 3 of the drawings, in which the roller 41 is disengaged from the spring 43 and the electric circuit opened. The star wheel 39 has as many arms and noses 38 as there are agitating elements provided on the device.

In operative relation to each post pair 13, is secured to the frame 11 a receptacle holding clip 51, adapted to keep a glass 52 or similar container in position upon the base plate 10. The clips are so arranged that they hold the glasses eccentrically in relation to the agitating elements 26, for a purpose hereinafter to be described.

The operation of this device is as follows: Let us assume that all of the heads 20, with the parts carried thereby, are in their elevat-

ed positions and it is desired to mix a drink in one of the receptacles 52. This receptacle, with the unmixed contents therein, is placed in position within one of the clips 51, after which the operator depresses the respective head 20 until the lug 36 has passed through the respective notch 37 in the frame member 12. By turning then the knob 32 in the direction of the arrow shown in Fig. 3 of the drawings, the said lug, by the intermediary of one of the noses 38, moves the star-wheel 39 correspondingly, thereby causing the roller 41 to bring the free end of the spring 43 into contact with the terminal screw 46, thereby closing the electric circuit of the motor 15. When the head 20 is lowered, its agitating element 26 is brought into mixing position within the receptacle 52 and the respective disk 18 into driving position relative to the friction disk 17. With the friction elements engaged, rotation is imparted to the agitating element, and the liquid thoroughly mixed in the receptacle 52.

The springs 25 are obviously stronger than the spring 50, the result being that the star wheel 39 is held in circuit closing position as long as any one of the heads 20 is in lowered position.

A plurality of drinks may be mixed simultaneously or successively, the circuit of the electric motor being adapted to be closed by any one of the lugs 36 and held closed as long as any one of these lugs is keeping the star wheel 39 against movement caused by the spring 50. The agitators are thus adapted to be operated successively, selectively or simultaneously, they having a common driving element, which is set into action by bringing any one of the agitating elements into operative position.

The split portions 29 of the agitating elements have a tendency to move the liquid outwardly and also upwardly, while the grooved stems of the agitating elements cause a movement of the liquid primarily outwardly, the longitudinal grooves permitting at the same time a continuous flow of air to the body of the liquid, thereby aerating the same. By disposing the agitating elements eccentrically in the receptacles 52, a thorough mixing of the ingredients is obtained.

Whenever a drink has been mixed to the desired degree, the respective knob 32 is turned so as to bring its lug 36 into alignment with the respective notch 37 in the frame member 12, the respective springs 25 causing then an upward movement of the head 20 and the elements carried thereby, thus permitting the receptacle to be removed from the base plate 10. When all of the heads are in their elevated positions, obviously the electric circuit is interrupted and the motor brought to a stop.

It is obvious that while herein three agi-

tating elements have been shown, the device may be constructed with more or less, according to the requirements, the invention residing mainly in the provision of a multiple mixer having agitating means grouped around a common driving element, in combination with a switch closing device that is adapted to be actuated by any one of the agitator carrying means.

10 What I claim is:—

1. A drink-mixer, comprising a main frame, an electric motor thereon, a friction disk driven by said motor, a plurality of heads slidably mounted on said frame, an agitating element rotatably mounted on each head, a wheel operatively connected with each agitating element adapted to be frictionally driven by said disk, a switch in the circuit of said motor, and oscillatable means carried by each head for holding its wheel, at will, in frictional contact with said disk, closing said switch when turned to holding position.

2. A drink-mixer, comprising a main frame, an electric motor thereon, a friction disk driven by said motor, a plurality of heads slidably mounted on said frame, an agitating element rotatably mounted on each

head, a wheel operatively connected with each agitating element adapted to be frictionally driven by said disk, a switch in the circuit of said motor, an oscillatable member capable of closing said switch, and means carried by each head for holding its wheel, at will, in frictional contact with said disk, actuating said switch closing mechanism when moved to holding position.

3. A drink-mixer, comprising a main frame, an electric motor thereon, a friction disk driven by said motor, a plurality of heads slidably mounted on said frame, an agitating element rotatably mounted on each head, a wheel operatively connected with each agitating element adapted to be frictionally driven by said disk, a switch in the circuit of said motor, and oscillatable member capable of closing said switch, and oscillatable means carried by each head for holding its wheel, at will, in frictional contact with said disk, actuating said switch closing mechanism when turned to holding position.

Signed at New York, in the county of New York and State of New York, this 18th day of January, A. D. 1922.

ELMER SAS.
